(57) **CLAIM**

The ornamental design for an exercise apparatus, as shown and described.

DESCRIPTION

FIG. 1 is a perspective view of an exercise apparatus.

FIG. 2 is an elevational view of one side thereof.

FIG. 3 is an elevation view of the opposite side thereof.

FIG. 4 is a rear elevational view thereof.

FIG. 5 is a front elevational view thereof.

FIG. 6 is a top plan view thereof; and,

FIG. 7 is a bottom view thereof.

The broken lines in FIGS. 1, 6 and 7 define bounds of the claimed design and forms no part thereof.
